UNITED STATES PATENT OFFICE.

ABRAHAM RYCKOFF, OF NEW YORK, N. Y.

SHIP-BED.

1,301,174.

Specification of Letters Patent. Patented Apr. 22, 1919.

Application filed August 27, 1918. Serial No. 251,626.

To all whom it may concern:

Be it known that I, ABRAHAM RYCKOFF, a citizen of the United States, residing at New York city, N. Y., have invented certain 5 new and useful Improvements in Ship-Beds, of which the following is a clear, full, and exact description.

My invention relates to beds and especially to beds for use on ship board where 10 it may be desired, at times, to swing the bed to a position to be out of the way. One of the principal objects of my invention is to construct the bed bottom of such a bed in such a manner that its parts may be cheaply 15 and conveniently made and readily assembled and be conveniently supported between stanchions such as are usually used for the purpose.

An important feature of my invention relates to the formation of the corner piece of 20 the bed, whereby it may carry the end and side rails together with the head or foot rails and the lee rails. In bed constructions as heretofore employed, it has been customary 25 to cast the side and end rails into the corner piece and to separately cast the lee rail with the side rail, and also to separately cast the head or foot rail with the end rail. With my improved construction, 30 the corner piece is provided with sockets into which fit the side, end, lee, head and foot rails.

Another important feature of my invention relates to the supporting bracket, said 35 bracket being so arranged that it is conveniently fastened to a stanchion when the bed is used on ship board, said bracket being formed for supporting either two or four beds as may be desired, the corner piece of 40 the bed being provided with a button which fits into a groove in the bracket, thus permitting a limited rotary movement of the corner piece in the bracket so as to enable the bed to be swung up out of the way.

Another important feature of my invention 45 relates to the manner of forming the sockets in the corner piece for the lee rail and for the head or foot rail whereby said rails act to tie the bed together.

Another important feature of my invention 50 relates to the formation of lugs or raised

portions within the socket for the end and side rails of the bed, whereby when said rails are driven into the socket a close fit is obtained.

55

Other important features and objects will appear from the following description taken in connection with the accompanying drawings in which:

Figure 1 is a perspective view of my improved corner piece showing the manner of engagement therewith of the several rails; 60

Fig. 2 is a perspective view of the corner piece looking into one of the sockets and showing the lugs projecting from the sides 65 thereof;

Fig. 3 is a top plan view of my improved bracket designed for the support of four beds, the said figure showing the corner piece of one bed engaging the bracket; 70

Fig. 4 is an end elevation showing a pair of beds swung from the supporting bracket carried by a stanchion;

Fig. 5 is an end view of four beds, two of the beds being arranged in a horizontal 75 plane with two others above them;

Fig. 6 is a side view of the bed;

Fig. 7 is a perspective view of my improved bracket designed for the support of four beds; 80

Fig. 8 is a perspective view of my improved bracket designed for the use of two beds; and

Fig. 9 is a modified form of bracket made of sheet metal. 85

Fig. 10, is an enlarged detail view of the form of bracket shown in Fig. 4.

End rails 2 and side rails 4 engage sockets in a corner piece 6, there being, of course, two end rails 2 and two side rails 4, which together with the four corner pieces 6, constitute the bed bottom. The corner piece 6 is in the form of a casting having sockets into which the rails 2 and 4 are designed to be tightly fitted. Projecting at right angles 90 to the plane formed by the end and side rails, is a socket 8, also formed in the casting 6, and into said socket is fastened the lee rail 10. Said rail is bent at right angles, as clearly shown in Fig. 1 and is riveted or 100 otherwise securely fastened to the corner piece 6 by securing means 12. While it is

desirable that the end and side rails shall fit tightly into the corner piece 6, it is not necessary for the purpose of holding the bed together that these rails be riveted or pinned 5 to the corner piece 6 because the lee rail 10 acts as a tie piece to tie the bed together longitudinally.

Also formed in the corner piece 6 is another socket 14 and into said socket is surely fastened the head or foot rail 16. 10 This foot rail not only serves its usual purpose of preventing the mattress from being displaced, but also serves the additional function of tying the bed together transversely, it being bent as shown in Fig. 1 for this purpose.

While, as stated above, it is not necessary with my improved construction that the end and side rails be riveted or otherwise securely fastened to the corner pieces 6 nevertheless, it is desirable that these rails shall fit tightly into said corner pieces and for the purpose of securing a tight fit when the side and end rails are driven into the corner 25 pieces, the socket of each corner piece designed to be engaged by an end or side rail, is formed with projecting lugs 18 as shown in Fig. 2.

When beds of this general character are 30 designed for use on ship board it is customary to arrange them in rows between decks and during the day time it is convenient to have the beds swung out of the way so as to afford a passageway between them. To provide for thus swinging the beds to a position where they will be out of the way, I form upon each of the corner pieces 6 a button 20 having a surface 22 adapted to seat on the bottom of the slot 35 24, in the bracket 28. (See Figs. 3 and 7.) This bracket 28 may be formed of a single casting for supporting four beds, as shown in Fig. 7, or it may be formed of a casting for supporting two beds, as shown in Fig. 8, 40 or said bracket may be formed from a single piece of sheet metal, as shown in Fig. 9. However formed, the bracket consists of a substantial channel shaped member having slots 26, formed therein, and having a central opening 30, through which the stanchion 45 passes, the bracket being rigidly fastened to the stanchion by suitable securing means. When the bracket is formed of sheet metal, I prefer to strike up tongues 31 through 50 which fastening means may pass to secure the bracket to the stanchion. It will be noted that the bracket may be used to support either two beds arranged head to head or two beds arranged side by side, and when 55 supporting two beds side by side only half of the bracket is used, the bracket being cut along approximately the line $a-b$, as indicated in Fig. 7, of course, leaving sufficient metal to entirely encircle the stanchion.

When used for supporting two beds head to 65 head, the form shown in Fig. 8 is used, the bracket being cut along substantially the line $c-d$, of Fig. 7.

In forming the bracket of a single piece of sheet metal, instead of striking up tongues 70 by which the bracket is fastened to the stanchion, I may prefer, in some cases, to merely cut a hole in the center of the sheet metal piece large enough to embrace the stanchion and pass a rivet through the bent 75 up sides of the bracket and through the stanchion.

It may be desirable at times, to use beds which do not need to be swung from horizontal position and when my bed is so used, 80 I construct it as shown in Fig. 5. But when the bed is designed to be swung from a horizontal position, I omit the lee rail at the side of the bed adjacent the stanchion. This is done because the lee rails of adjacent beds 85 would interfere with each other, unless the beds were placed a considerable distance apart, and on ship board where space is of great importance, it is, of course, desirable to have the beds as close together as practicable.

The beds are supported from the stanchions in any suitable manner, as, for instance, by a chain attached to a bracket secured to the stanchion, as shown at 32, Fig. 95 4, or I may cast the bracket with projecting lips 34, one coincident with each channeled side of the bracket and cast or drill holes in said lips into which the chains supporting the beds may be hooked. The other end of the chain may be hooked in any convenient manner to the bracket 6, as by hooking over the button 20, as shown in Fig. 4.

It will be particularly noted that the foot and head pieces 16 project horizontally 105 from the socket 14 in the corner piece 6 and are then bent upwardly and laterally. This form of construction provides for a mattress of standard length while, at the same time, the tubing of the side rails 4 is not required to be of full length. This will be readily seen from Figs. 1 and 3 and especially from Fig. 3 wherein it will be seen that the rails 16 of two beds are very close together and they may be made as close as 110 desired by slight changes in the relative dimensions of the parts forming the beds. When the bed is swung up from the position, shown in Fig. 3, the distance from the bend in the rail 16 from the stanchion is such 115 that there will be no interference, as the bed is not swung to a strictly vertical position, but to a position whereby it forms an angle with the vertical of somewhat less than 45°.

In assembling my improved bed, the side and end rails are driven into the sockets in the castings 6. These castings may be made

of ordinary cast iron or malleable iron. The lee and head or foot rails are then inserted and securely fastened.

It will thus be seen that with my improved construction, I have provided a bed which may be shipped in sections and put together at any time by the use of comparatively simple securing means, such as rivets, pins, metal screws or the like. I have also provided a bed which is cheap to manufacture and which when assembled is perfectly rigid.

What I claim as new is:—

1. In a bed, the combination with the side and end rails, a lee rail and a head or foot rail, of a corner piece having a socket adapted to receive the side rail, a socket adapted to receive the end rail, a socket adapted to receive the lee rail and a socket adapted to receive the head or foot rail.
2. In a bed, the combination with the side, end, lee and head or foot rails, of corner pieces each corner piece having a socket to receive the end rail and a socket extending at right angles thereto, to receive the head

or foot rails, said corner piece also having a socket to receive the side rails and a socket extending at right angles thereto, to receive the lee rail, said lee rail acting as a tie between two adjacent corner pieces lengthwise with the bed and said head or foot rail acting as a tie between adjacent corner pieces transverse the bed.

3. A corner piece for bed bottoms, formed as a casting having sockets for receiving the side and end rails of the bed, sockets for receiving the lee and head or foot rails of the bed and a projecting button for supporting the bed bottom.

4. A bracket for supporting beds, said bracket being formed of sheet metal struck up to form sides in which are cut grooves to support the beds and struck up from the center to form projections whereby the bracket may be attached to a supporting member.

Signed at New York this 21st day of August 1918.

ABRAHAM RYCKOFF.
